UNITED STATES PATENT OFFICE.

FRANK P. BACHMAN, OF AKRON, OHIO.

AMUSEMENT OR EXERCISING DEVICE.

1,248,056.

Specification of Letters Patent. Patented Nov. 27, 1917.

Application filed February 19, 1917. Serial No. 149,490.

To all whom it may concern:

Be it known that I, FRANK P. BACHMAN, a citizen of the United States, residing at Akron, in the county of Summit and State 5 of Ohio, have invented new and useful Improvements in Amusement or Exercising Devices, of which the following is a specification.

This invention has relation to amusement 10 or exercising devices of that type wherein the effect of the delivery of a blow by the user of the device against a suitable portion thereof is adapted to set other mechanism in operation whereby the strength or force of 15 the blow is either recorded or indicated, and the object of the invention is the provision of novel mechanism of the general type described, which will furnish amusement and exercise to the user and which when used 20 by two or more persons may constitute a game apparatus. More specifically the invention comprises a frame on which are mounted a plurality of pulleys or the like, quadrilaterally disposed in imitation of the 25 respective position of the bases of a base ball diamond and having extending around said pulleys a flexible member such as a cable bearing a miniature toy figure simulating a base ball runner. The device has further 30 provision for shifting the flexible member longitudinally around said pulleys upon the delivery of a blow to suitable mechanism having connection with said member and so arranged that the length of movement or 35 distance traveled by the figure from the initial starting point is proportional to the impact of the blow delivered. Means are also provided for returning the member and figure to their original positions upon the 40 termination of the forward movement of the member and toy figure so that the device is then ready for reuse.

With the foregoing and other objects in view, the invention consists in the novel 45 construction, combination and arrangement of parts constituting the invention to be hereinafter specifically described and illustrated in the accompanying drawings which form a part hereof wherein is shown the 50 preferred embodiment of the invention, but it is to be understood that changes, variations and modifications may be resorted to which come within the scope of the matter hereinafter claimed.

55 In the drawings in which similar refer-

ence numerals indicate like parts in the different figures,

Figure 1 is a view in front elevation of a device embodying the present invention.

Fig. 2 is a transverse sectional view of a 60 portion of the device shown in Fig. 1, taken upon line 2 thereof.

Fig. 3 is a view partly in side elevation and partly in section of the device shown in Fig. 1.

Fig. 4 is a vertical, central, sectional view 65 enlarged of the upper portion of the device.

Fig. 5 is a view similar to Fig. 4 of the more central portions of the device, and

Fig. 6 is a sectional view of the impact or 70 blow receiving member employed in the device.

Referring to the drawings in detail the device embodies a pair of upright standards 1-1 connected near their lower portions by 75 a cross bar 2. Extending between the upper portions of the posts 1-1 is a horizontal connecting bar 3. Secured to the upper end of the posts 1-1 by holding members 4 is a quadrilaterally formed member simulating 80 the general form of a base ball diamond. The member 5 is preferably composed of two parallel coöperating members 6 and 7 having formed between them a channel 8. The member 6 is provided with a recessed portion 85 through which extends a pin 9 constituting a pivot for a sheave 10. This recessed portion is arranged at one of the angles or intersections of two of the side forming members at the right of Fig. 1. The 90 member 5 is also provided at the junction of the two other side members or arms of the device with a recessed portion through which extends a shaft 11 constituting a pivot for a sheave 12. The shaft 11 extends rearwardly through the member 5 for a purpose 95 to be later described. At the angle between the members of the device at the left the member 6 is provided with a recessed portion through which extends a pin 13 constituting a pivot for a sheave 14. At the lower portion of the device the inner member 6 is provided with an enlargement 15 provided with a recess through which extend pins 16 and 17 constituting pivots for 100 sheaves 18 and 19 respectively. The entire frame is stiffened by means of a brace 20 the lower end of which is adapted to rest on suitable foundation and is connected by means of a bar 50 with the bar 2 and the up- 105

110

per end thereof is connected by a coupling member 21 with the upper portion of the member 7 at the vertex or upper angle of the member 5. The brace 20 is provided with a bearing for a shaft 11, and mounted on this shaft 11 is a sheave 22.

Mounted on the cross bar 3 is a bearing 23 for a horizontal shaft 24 the rear end of which is suitably mounted in the bearing 25 secured to the brace 20. Mounted on the front end of the shaft 24 is an impact receiving arm 26 in the form of a crank preferably terminating at its free end in a head 27 which is covered with some cushioning material 28 preferably of resilient quality and usually spherical in contour to resemble the general shape and size of an ordinary base ball. Mounted on the shaft 24 in front of the bearing 23 is a sheave 29 and rearwardly of the bearing 23 is a sheave or drum 30. The arm 26, sheave 29 and the drum 30 are all fixedly secured at the shaft 24 and revolve therewith.

Extending in the groove or channel 8 of the member 5 and seated in the grooved faces of the pulleys 10, 12, 14, 18 and 19 is a flexible member 31 preferably comprising a cable or cord and this member extends upwardly after passing partially around the grooved face of the pulley 19 and is wound one or more times around the sheave 29 and from thence downwardly partially around the sheave 18 and then around the sheaves 14, 12 and 10. This flexible member 31 is in a taut condition so as to frictionally engage the sheave 29 and be moved by the revolution thereof. Secured to and preferably wrapped one or more times around the drum 30 is a flexible member such as a cable 33 which extends upwardly around the sheave 22 and then downwardly as shown in the drawings and to the lower end of which is connected a counter-weight 34. Mounted on the flexible member 31 is a carrier 35 adapted to travel in the channel or groove 8 and which bears, outside of the channel, a toy figure 36 usually simulating in miniature a base ball player in conventional uniform. The toy figure 36 when the device is at rest will be positioned at 37 adjacent to the sheave 19 which in the use of the device constitutes the home plate.

The device is used by striking the cushioned free end of the impact arm 26 with some instrument such as a base ball bat, which causes a rapid rotation of the shaft 24 and sheave 29 thereby moving the member 31 and the toy figure 36 along the groove 18 around the sheaves 10, 12 and 14 which may be designated for convenience as first, second and third base positions and finally to the sheave 18. The amount of travel of the toy figure will be directly proportional to the force and quality of the blow on the end of the impact arm 26, that

is to say by way of illustration a light blow may cause the figure to travel as far as the sheave 12 and a blow of greater effectiveness may make the figure travel to a point between the sheaves 14 and 18 or to any other position. The rotation of the shaft 24 causes the drum 30 to wind upon the flexible member 33 thereby raising the counter-weight 34 and when the progressive movement of the toy figure 36 ceases the counter-weight 34 acting by gravity upon the drum 30 will rotate the shaft 24 in a reverse direction which through the connected mechanism returns the figure to its initial or original starting position. From the foregoing it will be seen that the device may be used as a strength testing device, as an exercising device, as an amusement device and when two or more persons agree in the use of the device, it may constitute a game apparatus.

I claim:

1. A device of the class described comprising a support, a channeled frame mounted thereon, a flexible member shiftably mounted in the channel in said member, idler sheaves in said frame the peripheral portions of which support said member in said channel, a driving sheave around which is wrapped said member, an impact receiving arm connected with said driving sheave, and arranged when revolved to shift the position of said member, an indicator carried by said member and movable in unison therewith through said channel, and means for returning said member and indicator to their initial positions upon the cessation of the movement of said arm.

2. A device of the class described comprising a support, a polygonal frame having a facial channel therein mounted on said support, a flexible member shiftably mounted in the channel in said frame, idler sheaves mounted in said frame and disposed at the angles thereof the peripheral portions of which support said member in said channel, a driving sheave positioned within the space inclosed by said frame and about which said member is wrapped, an impact receiving arm connected with said driving sheave and arranged when revolved to shift the position of said member, an indicator carried by said member, and means for returning said member and indicator to their initial positions upon the cessation of movement of said arm.

3. A device of the class described comprising a support, a polygonal frame having a facial channel therein mounted on said support, a flexible member positioned in the channel in said frame, idler sheaves mounted in said frame and disposed at the angles thereof the peripheral portions of which support said member in said channel, a driving sheave positioned within the space inclosed by said frame and arranged to be engaged by said member, an impact receiving

- arm connected with said driving sheave and arranged when revolved to shift the position of said member, an indicator carried by said member, a drum having connection with said 5 driving sheave, a flexible member wound on said drum, a counterweight on said flexible member, said flexible member arranged to be wound up by the rotation of said driving sheave under the influence of a blow.
- 10 4. A device of the class described comprising a pair of upright supports, a bar extending between said supports, a bearing on said bar, a shaft in said bearing, an impact receiving arm mounted on said shaft, a sheave 15 and a drum also mounted on said shaft, a channeled frame disposed about said bearing, idler sheaves positioned in said channeled frame with the peripheral portions thereof in said channel, a flexible member 20 extending around said idler sheaves and around the sheave on said shaft whereby said flexible member is shifted by the revolution of said impact arm, an indicator carried by said flexible member and movable in unison therewith through said channel, a 25 flexible member having connection with said drum and arranged to be wound thereon when said shaft is rotated by a blow delivered to said impact arm, a counterweight on the flexible member on said drum and raised by the rotation thereof, and arranged to reversely rotate said drum upon the cessation of movement of said shaft to return said indicator to its initial position.
5. A device of the class described comprising a pair of upright supports, a bar extending between said supports, a bearing mounted on said bar, a shaft in said bearing, an impact receiving arm mounted on said shaft, a sheave and a drum also mounted on said shaft, a channeled frame disposed about said bearing, idler sheaves positioned in said channeled frame with the peripheral portions thereof in said channel, a flexible member extending around said idler sheaves and around the sheave on said shaft whereby said flexible member is shifted by the revolution of said impact arm, an indicator carried by said flexible member and movable in unison therewith through said channel, a flexible member having connection with said drum and arranged to be wound thereon when said shaft is rotated by a blow delivered to said impact arm, a counterweight on the flexible member on said drum and raised by the rotation thereof, and arranged to reversely rotate said drum upon the cessation of movement of said shaft to return said indicator to its initial position. 30 35 40 45 50 55

In testimony whereof I have hereunto set my hand.

FRANK P. BACHMAN.
